UNITED STATES PATENT OFFICE.

WILLIAM FROHNE, OF CINCINNATI, OHIO.

MOP-WRINGER.

1,170,623.

Specification of Letters Patent.

Patented Feb. 8, 1916.

Application filed April 18, 1914. Serial No. 832,797.

To all whom it may concern:

Be it known that I, WILLIAM FROHNE, a citizen of the United States, residing at Cincinnati, in the county of Hamilton and State 5 of Ohio, have invented new and useful Improvements in Mop-Wringers, of which the following is a specification.

The present invention relates to improvements in wringing devices for mops or the like, the object being to simplify and improve the existing art by providing an apparatus of this class having rollers arranged upon hinged cover sections in such a manner that the same will effectively engage 10 with the mop when the same is arranged therebetween and moved in a vertical direction to wring the water from the mop, the said hinged cover sections being separated by a pull in opposite angular directions only 15 for the insertion of the mop between the rollers, or the removal of a receptacle arranged within the device to catch the water wrung by the rollers from the mop.

Another object of the invention is to provide 20 a wringer wherein the employment of springs or adjusting elements is entirely dispensed with.

With the above and other objects in view, the improvement resides in the construction, combination and arrangement of parts 30 set forth in the following specification and falling within the scope of the appended claims.

In the drawings: Figure 1 is a perspective view of a wringer constructed in accordance with the present invention, Fig. 2 is a transverse sectional view illustrating the hinged cover sections swung to an open position to permit of the insertion or removal 40 of the bucket as well as the arrangement of the mop between the rollers, Fig. 3 is a similar sectional view showing the hinged cover sections of the same swung to permit of the insertion of the mop between the rollers, Fig. 4 is a similar sectional view but showing the mop gripped between the rollers, and Fig. 5 is a top plan view of the device showing the hinged cover sections in an open position.

Referring now to the drawings in detail, the numeral 1 designates a receptacle which, in the form illustrated by the drawings, is square or rectangular, including sides 2-2, ends 3 and 4 respectively and a base or bottom 5. The bottom preferably extends beyond the sides and ends to provide what

may be termed a horizontal flange and which may receive the weight of the operator when his feet are positioned upon the said flange during the operation of extracting 60 the excess water from the mop. The sides 2, have their upper edges arranged flush with the upper edge of the end 3 for approximately one-half of the length of the said sides, the said upper edges being indicated 65 by the numerals 6. The upper edges of the sides 2 at their opposite ends, for a slight but suitable distance, are arranged in a line with the upper edge of the end 4, as indicated by the numeral 7, while said upper 70 edges are inclined from the walls 6 and 7, as indicated by the numeral 8.

The top of the receptacle 1 is provided with a pair of hinged cover sections in the nature of box-like covers which are indicated by the numerals 9 and 10 respectively. The cover section 9 is hingedly connected with the side 3 of the receptacle, as at 11, while the cover section 10 is hinged to the end 4, as at 12. The cover section 9 includes 80 sides 13 and an end 14. The lower edges of the sides and ends are parallel with the upper edges thereof, the end being of a length equaling that of the end 3 of the receptacle, while the lower edges of the sides 85 are of a length equaling that of the horizontally straight upper edges 6 of the sides 2 of the receptacle. The sides 13 have their forward edges formed with tongues 15, which are provided by beveling the outer 90 faces of the said sides from the lower edges thereof to the vertically straight edge 16 of the said sides, or the edge which is arranged parallel with the end 14 of the said cover section. 95

The numeral 17 designates a rectangular member, which is secured to both the sides 13 and the end 14 of the top of the cover section 9 and to the outer edge thereof, the said rectangular member serving as a wiper, 100 as will hereinafter be apparent. The end 14 is formed with an elongated longitudinally extending opening 18 which serves as a hand grip whereby the member 9 may be swung upon its hinges 11 away from the 105 receptacle. The cover section 10 also comprises sides 19 and an end 20, the end being of a width corresponding with the width of the end 4 of the receptacle 1, and it will be noted that its hinges 12 are arranged upon 110 the receptacle a distance below the hinges 11 which connect the cover section 9 with

the receptacle. The end 20 is provided with an elongated longitudinally extending opening 21 similar to the opening 18 and which serves as a hand grip for swinging the section 10 toward the receptacle or away from the same. The sides at their connection with the end 20 have their lower edges horizontally straight, as at 22, the said portions resting upon the straight portions 7 in the upper edge of the sides 2 of the receptacle 1, and the said lower edge of the sides 19 is beveled or inclined, as at 23, to rest upon the inclined upper edges 8 of the sides 2. The said lower edges of the sides 19, beyond the inclined edge or wall 8 are formed with angular cut-away portions or depressions 24 which rest directly over the beveled outer edges of the tongues 15, while the outer vertically straight walls or edges 25 of the sides 19 abut with the vertically straight portions 16 on the inner edges of the sides 13 of the cover section 9. The upper edges of the sides and end of the cover section 10 are disposed in the same plane as the upper edges of the sides and end of the cover section 9, but the said upper edges of the sides 19, at a suitable distance from the meeting edges of the sides are beveled downwardly, as at 26, and from thence are beveled upwardly in an outward direction, as at 27, a plate being arranged upon the respective beveled walls, the plate being bent to form the portions 29 and 30 which conform to the beveled portions 26 and 27 respectively. The end 31 of the plate adjacent the portion 30 thereof is bent out of the plane of the portion 30 and adapted to rest upon the upper edges of the sides 19 and end 20 and the opposite end 32 is bent and adapted to rest on the upper edges of the sides 19. This plate 32 serves as a wiper, as will herein-after be more fully set forth, while the angular depressed portions 29 and 30 provided by the plate serve as a rest for the head of a mop when the mop proper is passed over the wiper 32 and arranged within the receptacle or when the said mop is within the receptacle, or when the said mop is disposed between the wringer rollers carried by the cover sections 9 and 10, as will now be described.

The rollers are indicated by the numerals 33 and 34 respectively, both of the same being of a similar size and each having its ends provided with trunnions 35 and 36 respectively, the trunnions 35 of the rollers 33 passing through suitable openings formed in the sides 13 of the cover section 9 adjacent the inner upper corner thereof, the trunnions 36 of the roller 34 likewise finding bearings in openings formed in the sides 19 of the cover section 10 and arranged adjacent the inner corners thereof. The rollers 33 and 34 are thus arranged parallel and suitably spaced to allow a mop to be drawn

between them, and it will be noted that by swinging the sections 9 and 10 to an open position, the mop may be readily arranged between the rollers and compressed thereby that by inclining the mop the same may be deposited within a bucket or similar utensil 37 which is arranged within the receptacle 1 for such a purpose. It will be further noted that by inclining the mop the same may be brought over either of the scrapers 17 or 32 either after the water has been compressed from the same by the rollers, or when it is desired to merely remove the dirt or other substances collected by the mop.

Secured upon the inner face of each of the sides 19 of the cover section 10, and disposed thereon approximately in a line with the juncture of the walls 23 and 24 of the said sides, are horizontally extending rods 38 and 39 respectively, the said rods having the upper edges of their portions which extend beyond the cover section 10 curved downwardly and terminating in an upset or angular portion to provide hooks 40. The sides 13 of the cover section 9, adjacent the tongues 15, are provided with laterally extending studs or pins 41 which are adapted to bear upon the inclined or rounded upper edges of the bodies of the hooks 38 and 39 when the cover sections 9 and 10 are in operative position as shown in Figs. 1, 3 and 4. By virtue of the hooks and studs the outward swinging movement of the cover sections 9 and 10 will be limited when drawn up to place the mop between the rollers 34 and 35.

When it is desired to swing the sections 9 and 10 to their fully open position, after the same have been partially opened, as just described, and retained against further opening by the contacting of the hooks 40 with the pins, it is merely necessary to release the pressure upon the member 10, allowing the same to drop to bring the offset portions or hooks proper below the pins, then the sections may be independently swung to bring their end portions 14 and 20 respectively against the ends 3 and 4 of the receptacle.

From the above description, taken in connection with the drawings, it will be noted that I have provided a simple, cheap and thoroughly efficient device for the purpose designed, wherein the employment of springs or analogous devices for forcing the rollers toward each other, is entirely dispensed with, and wherein the roller-carrying members are provided with wipers so that an accumulation of dirt or foreign matter may be removed from the mop by merely drawing the mop over the said wipers, and also that I have constructed the top of the section 10 to form a rest for the head of the mop when the mop is not required for immediate use.

Having thus described the invention, what I claim is:

1. In a device of the class described, a receptacle having rectangular ends and adapted to receive a pail, a cover section including an end hinged to one end of the receptacle and sides resting upon the upper side edges thereof, the sides of said cover section having angular tongues at the lower inner corners thereof, a second cover section also including an end hinged to the remaining end of the receptacle and sides resting upon the upper sides of the receptacle, said sides being recessed to receive the tongues on the sides of the first mentioned cover section and having their ends abutting with the ends of the sides of the first mentioned cover section, a roller carried by each of the cover sections, said rollers being adjacent and disposed in parallel relation, hooks secured to the inner faces of the sides of one of the cover sections and extending along the sides of the other cover section, and pins extending laterally from the inner faces of the sides of the second mentioned cover section and bearing upon the extending portions of the rods.
2. A substantially rectangular receptacle having an opened top, a cover section having sides and an end resting upon the upper edges of the receptacle at one end thereof, the sides of said cover section having at

their inner edges portions which are inclined upwardly from the lower ends thereof to provide the same with tongues, a roller 35 trunnioned between the sides of the cover section, pins disposed below the roller projecting laterally from the sides, a top plate arranged adjacent the roller, a hinge connection between the end of the cover section 40 and the end of the receptacle, a second cover section comprising sides and an end, a hinge, connection between the end and the second end of the receptacle, said sides at their inner ends being inclined to provide recesses for the reception of the tongues of the first mentioned cover section, a roller 45 trunnioned between the sides of the second mentioned cover section and parallel with the roller of the first mentioned cover section, longitudinally extending rods secured to the sides of the second mentioned cover section and provided with extending ends terminating in hooks, said rods contacting with the laterally extending pins on the 50 first mentioned cover section, and a plate disposed upon the top of the second mentioned cover section adjacent its roller.

In testimony whereof I affix my signature in presence of two witnesses.

WILLIAM FROHNE.
